(57) **CLAIM**

The ornamental design for a portable information terminal stand, as shown and described.

DESCRIPTION

FIG. 1 is a perspective view of a portable information terminal stand showing our new design;

FIG. 2 is a front elevational view thereof;

FIG. 3 is a rear elevational view thereof;

FIG. 4 is a top plan view thereof;

(Continued)

FIG. 5 is a bottom plan view thereof; and,
FIG. 6 is a right side elevational view thereof, a left side
elevational view being a mirror image of the right side
elevational view thereof.

1 Claim, 6 Drawing Sheets
